[57] CLAIM

The ornamental design for a tool for use in removing nail polish from finger nails, as shown and described.

DESCRIPTION

FIG. 1 is a front elevational view of a tool for use in removing nail polish from finger nails showing my new design;

FIG. 2 is a back elevational view thereof;

FIG. 3 is a left side elevational view thereof, the right side elevational view being a mirror image of FIG. 3;

FIG. 4 is a bottom plan view thereof;

FIG. 5 is a top plan view thereof; and,

FIG. 6 is a top front perspective view thereof.
